UNITED STATES PATENT OFFICE.

FRED E. YATES, OF MINNEAPOLIS, MINNESOTA.

VALVE FOR GAS-BURNERS.

1,034,669.

Specification of Letters Patent. Patented Aug. 6, 1912.

Application filed January 15, 1912. Serial No. 671,179.

To all whom it may concern:

Be it known that I, FRED E. YATES, a citizen of the United States, residing at Minneapolis, in the county of Hennepin and State of Minnesota, have invented a new and useful Valve for Gas-Burners, of which the following is a specification.

This invention relates to safety valves for gas burners.

10 The primary object of the invention is to provide means acted upon by the gas flame to hold the gas valve open, said means closing said valve when the flame is extinguished.

15 In the drawings, Figure 1 is a perspective view of the device applied to a gas burner. Fig. 2 is a side elevation. Fig. 3 is a section on the line A—B of Fig. 2, and Fig. 4 is a detail view showing the connection between the valve rod and the weighted closure for the valve.

In the drawings, 10 designates the gas burner, gas being admitted to the same by the valve 11, actuated by the valve rod 12.

20 A bracket 14 is secured to the burner 10, said bracket being formed of a single piece of metal the body portion of which is bent to embrace the burner, the apertured extensions 15 of said body portion being connected by the screw 16, in order that the same may be clamped upon the burner. The arm 17 of the bracket is offset from the same and extends upwardly, and secured to said arm is a bar 18 which is formed intermediate its ends with a yoke 19. This bar is secured at either end to a vertically extending arm 20 the lower ends of the arms 20 being curved to engage the sliding weighted member 26. A second bar 24, similar in construction to the bar 18, is secured to said arm, and the two bars combine to form a guide for said sliding weighted member. This sliding weighted member 26 is provided with the head 27, to prevent the same

40 from falling between the transverse bars 18 and 24, the end portion of the bar being connected to the valve rod 12 as shown in detail in Fig. 4. The yoke 28 has its end portion connected to the upper terminals of the arms 20, said yoke extending over the burner.

The burner is lighted after the valve rod 12 has been lifted, said valve rod being held

until the yoke 28 has been sufficiently heated to expand. When this yoke has expanded, 55 the curved ends of the arms 20 will be moved to grasp the sliding member 26, the arms having a pivotal connection with the transverse bars which allows the yoke to force the same into contact with the sliding 60 bar. Thus, as long as the yoke is maintained in its expanded position the sliding valve operator will be held raised, the valve being maintained open. To close the valve, the rod 12 is manipulated and the sliding 65 valve operator allowed to fall. It will be noted that should the flame be extinguished without the valve being closed, the cooling and contraction of the yoke 28 will separate the lower terminals of the arms 20, permitting the weighted rod 26 to fall, which will, through the medium of the rod 11, close the valve and cut off the supply of gas.

It will be seen that a construction of this character will cut off the flow of gas should 75 the flame be extinguished without manipulating the valve. Attention is also called to the fact that the device may be easily and economically constructed, being readily applied to burners now in use.

What is claimed is:

1. A valve actuating mechanism for gas burners comprising a bracket supported by the gas burner, a bar supported by said bracket, a plurality of arms pivotally supported by said bar, a second bar connecting said arms, said bars being formed intermediate their ends with yokes, a weighted valve operator slidably mounted between said bars, the terminals of said arms being offset to 90 contact with said sliding valve operator, and an expansible yoke secured to said arms.

2. A valve actuating mechanism for gas burners comprising a bracket supported by the gas burner, a plurality of pivoted arms supported by said bracket, a valve operator slidably mounted between said arms, and an expansible yoke connecting said arms.

In testimony that I claim the foregoing as my own, I have hereto affixed my signature 100 in the presence of two witnesses.

FRED E. YATES.
